BEADED FLORAL CANDLEHOLDER DECORATION

Margaret R. Wender, 4201 Cathedral Ave. NW.,
Washington, D.C. 20016

Filed Mar. 10, 1967, Ser. No. 6,151

Term of patent 14 years

(Cl. D48—2)

The broken line showing of a candle and holder therefor in FIGURE 1 is for illustrative purposes only. The bead elements in FIGURES 1 and 2 are understood to be like those shown in FIGURE 3 and have been so shown for convenience of illustration.

I claim:

The ornamental design for a beaded floral candleholder decoration, as shown and described.
